UNITED STATES PATENT OFFICE.

ALBERT E. MOORE, OF HANSBORO, NORTH DAKOTA.

POT DRAINER.

Application filed January 3, 1925. Serial No. 336.

To all whom it may concern:

Be it known that I, ALBERT E. MOORE, a subject of the King of England, residing at Hansboro, in the county of Towner and State of North Dakota, have invented certain new and useful Improvements in Pot Drainers, of which the following is a specification.

This invention relates to new and useful improvements in pot drainers, and more particularly to a device for enabling a person to handle a receptacle to be drained while the same is hot, thus preventing any injury to the person handling the same.

10 A still further object of the invention is to provide a means which is adapted to be easily and quickly placed in an operative position upon a receptacle to be drained, whereby the latter may be easily tilted in

20 order to drain the same.

Another important object of the invention is to provide a pot drainer which is especially adapted for use in conjunction with pots having the usual swinging bails thereon wherein means is associated with the device for holding the bail in a raised position, thus enabling the easy and quick operation of the tilting of the pot when the same is drained.

25 A still further object of the invention is to provide a device of the above mentioned character, which is simple in construction, inexpensive, strong and durable and further well adapted for the purposes for which it is designated.

30 Other objects and advantages of this invention will become apparent during the course of the following description.

In the accompanying drawing forming a part of this specification and in which like numerals designate like parts throughout the same,—

40 Figure 1 is a side elevation of a cooking receptacle with my invention applied thereto.

45 Figure 2 is a section on the line 2—2 of Figure 1.

Figure 3 is a section on the line 3—3 of Figure 1, and

50 Figure 4 is a detail perspective view of the frame.

In the drawing, wherein for the purpose of illustration is shown the preferred embodiment of my invention, the numeral 1 designates generally the frame forming a part of the device and the same may be

formed of any suitable material, such as wire, although it is to be understood that any other material may be substituted therefor. The frame 1 has its intermediate portion 2 looped and the arms 3 and 4 extend from the looped portion 2 in substantially parallel spaced relation. The arms 3 and 4 are bent downwardly adjacent the looped portion 2 thereof as shown at 5 in the drawing, and the free ends 6 and 7 respectively of the arms are also directed downwardly as shown at 8 in the drawing. A suitable connection such as is illustrated by the numeral 9 in the drawing is adapted to extend across the arms 3 and 4 at the point where the free ends 6 and 7 are bent downwardly. The purpose of the above construction will hereinafter be more fully described.

Formed in each of the arms of the frame 1 at spaced intervals are the loops 10 and 11, respectively. The loops are arranged in such a manner as to have the loops on one of the arms registering with the loops formed in the other arm, and it is to be understood that these loops are preferably formed in the intermediate portions of the arms by bending the free ends 6 and 7 previous to the formation of the down turned portions of the arms and the application of the cross member 9, as heretofore described.

These looped portions 10 and 11 form a means for pivotally supporting the lower free ends of the handles 12 and 13, respectively. The handles are also formed of the same material as the frame and are substantially U-shaped so that the ends of the arms thereof will form a means for permitting the handles to be pivotally associated with the looped portions of the frame, in the manner as clearly illustrated in the drawing. It is to be also understood that the handle 12 is slightly larger in width than the handle 13 so as to permit the arms of the handle 13 to be disposed between the arms of the handle 12 when the handles are crossed as is also illustrated in the drawing. The purpose of this construction will also be hereinafter more fully described. If desired, the crown portion of the handle 12 may be provided with a smaller handle 14.

In use, my device is adapted to be placed on the receptacle A in such a manner as to have the arms 3 and 4 of the frame 1 extending across the cover B which is provided for the receptacle A, and is loosely supported thereon in the usual manner. The handles

12 and 13 are then crossed so that the bail C of the receptacle A will rest on the cross portions of the handles, and at the same permitting the upper portions of the handles 5 to be grasped. If desired, the upper portions of the handles may be slightly curved inwardly so as to facilitate the grasping of both handles by the operator in one hand. The downwardly directed portions 6 and 7 10 of the arms 3 and 4 will abut one of the sides of the receptacle A and when in this position, the down turned portion 5 will provide a handle to be grasped by the other hand of the operator when it is desired to drain the 15 receptacle.

The operation of the device when in position may be briefly stated as follows:— The handle 5 is grasped in one hand and the handles 12 and 13 are grasped in the 20 other and by exerting a pressure on the handles 12 and 13, the bail C will be tightly grasped and thus permit the receptacle to be tilted and causing a downward pressure of the arms 3 and 4 on the lid or cover B, 25 whereby the liquid within the receptacle A may be easily drained therefrom without causing the hands of the operator or person handling the receptacle to become scalded or burned.

30 The simplicity of my device enables the same to be used on any kind of receptacle having a swinging bail and is of such a construction as to permit the ready and easy appliance of the same in position on the receptacle whenever it is desired to drain the latter. Furthermore, my device may be 35 manufactured at a minimum cost and is also easily operated.

From the foregoing description of the

construction of my improved apparatus, it 40 will be seen that I have provided a simple, inexpensive and efficient means for carrying out the objects of the invention, and while I have particularly described the elements best adapted to perform the functions set 45 forth, it is obvious that various changes in form, proportion, and in the minor details of construction may be resorted to, without departing from the spirit or sacrificing any of the principles of the invention. 50

Having thus described my invention, what I claim as new is:—

In a device of the class described, the combination with a receptacle including the bail thereof and a removable cover for said receptacle; of means for facilitating the tilting of said receptacle comprising a frame formed from a single strand of wire looped and bent intermediate of its ends to provide a pair of parallel arms and a looped 60 portion at one end forming a handle, the opposite ends of the arms being bent downwardly to form engaging ends, the arms being looped intermediate of their ends to form pairs of aligning eyes, a pair of inverted U-shaped handle members having their lower ends bent inwardly and engaged with the pairs of aforesaid eyes, said handle members being crossed beneath said bail and having their upper portions extended above 70 and on opposite sides of the crown of said bail; and link members connecting the upper end portions of said U-shaped handles above said bail, as and for the purposes described. 75

In testimony whereof I affix my signature.

ALBERT E. MOORE.
